UNITED STATES PATENT OFFICE

EDWARD J. FILBURN, OF TERRE HAUTE, INDIANA

SLIDER RAIL CLAMP

Application filed December 30, 1929. Serial No. 417,522.

This invention relates to a clamp for slider rails used particularly in mines.

As the entries, rooms or tunnels in mines are advanced a considerable distance a pair of rails known as work-ways are permanently laid on the ties in the well known manner. When the tunnel is further advanced a short distance, another pair of rails are laid on their sides, known as slider rails until the tunnel is far enough advanced to extend the work-ways. The tops of the slider rails fit into the grooves of the work-way rails the same being held together.

The object of this invention is to design a clamping means simple in structure that is adapted to hold the slider rails and work-ways securely together.

Reference is now had to the accompanying drawings wherein:—

20 Figure 1 is a cross-sectional view of the slider rail clamp in operative position, and

Figure 2 is a plan view thereof.

The slider rail clamp 10 is preferably made of a steel plate rectangular in form and comprises a bottom 11, a back 12 substantially at right angles to the bottom 11, and an inwardly bent portion 13 which is spaced from the bottom 11. The inner edge 14 of the inwardly bent portion 13 is parallel to the surface 30 of the back 12.

Positioned transversely to a work-way rail 15, in the manner shown in Figure 1, is a slider rail 16. To maintain the same in engagement, the slider clamp 10 is slid under both rails, the bent over portion 13 engaging the flange 17 of the work-way rail 15 as shown. Between the flange of the slider rail 16 and the back 12 of the clamp 10, is a wood plank 19 which serves as a wedge to securely 40 lock all of said elements together.

While a preferred embodiment of slider rail clamp has been shown, the same is nevertheless susceptible of various modifications within the scope of the appended claim.

45 Having thus described my invention, what I claim as new and desire to secure by Letters Patent is:—

An inexpensive slider rail clamp comprising a flat rail supporting bottom, and one end of said bottom projecting upwardly at right

angles thereto and then inwardly to cooperate with the flange of a work-way rail, the other end thereof being folded at right angles to the bottom of the clamp to cooperate with the bottom of a slider rail, said latter folded 55 upturned end lying within the same plane, said clamp being adapted to have a wedge inserted between the bottom of the slider rail and the upturned end cooperating therewith, whereby said wedge may be inserted or re- 60 moved from the upper side.

In testimony whereof I affix my signature.

EDWARD J. FILBURN.
